UNITED STATES PATENT OFFICE.

ALLAN E. LARD, OF WASHINGTON, DISTRICT OF COLUMBIA.

SHAFT FOR GOLF CLUBS AND THE LIKE.

Application filed May 10, 1921. Serial No. 468,260.

This invention pertains to shafts or handles for golf clubs and other implements and its principal object is to construct from bamboo, shafts which are inexpensive and at the same time just as effective in all such essentials as weight, "balance", flexibility, torsion, and strength, as the present very expensive ones.

Several embodiments of my invention are disclosed in the annexed drawings, wherein:

Fig. 1 is a sectional elevation of a shaft made in accordance with my invention;

Fig. 2 a like view of a modified form;

Fig. 3 a view illustrative of a handle or shaft extension attached to a bamboo shaft;

Fig. 4 a sectional elevation of a length of bamboo showing one manner of cutting the same to produce the desired taper in the ultimate shaft;

Fig. 5 a sectional elevation of a shaft wherein the blank shown in Fig. 4 is employed;

Fig. 6 a cross sectional view (enlarged) on the line VI—VI of Fig. 2;

Fig. 7 a view similar to Fig. 6 showing a modified construction of the reinforcing sleeve;

Fig. 8 an end view looking at the right hand end of Fig. 4;

Fig. 9 a like view illustrating a bamboo length having six V cuts extending lengthwise thereof;

Fig. 10 an elevation showing a filler for the grooves or depressions which are present in the bamboo length;

Fig. 11 a sectional view showing the manner of forming and preparing the lower or smaller end of the shaft for insertion in the wooden head;

Fig. 12 a similar view showing such head inserted;

Fig. 13 a like view illustrating the manner of securing the shaft in an iron;

Fig. 14 a sectional elevation of a shaft or handle such as would be suitable for a hammer;

Fig. 15 an end elevation thereof; and

Fig. 16 a side elevation of a portion of a shaft showing another modification.

Hickory shafts for drivers and brassies are about 42 inches long and are approximately three-fourths of an inch in diameter at the upper end and taper to about one-half inch at the lower end. It is this taper

of one-quarter of an inch in 42 inches that 65 properly distributes the weight and gives the shaft its correct "balance" and at the same time makes it more flexible ("whippy") towards the lower end. There is very little taper in a 42 inch length of bamboo three-quarters of an inch in diameter. The weight is therefore not properly distributed and it is not sufficiently flexible towards the lower end to make an effective shaft. A smaller size, say five-eighths of an inch at the upper 60 end has more taper but is lacking in stiffness towards the middle and upper end.

These defects are inherent in the growth of bamboo and are fatal to an ideal and effective golf shaft. I overcome these inherent defects in two ways: First, I start with the smaller bamboo 1, Fig. 1, say five-eighths of an inch, which is, as before stated, too flexible towards the upper part. I stiffen this upper part by turning same down 75 slightly and sliding over this turned surface a sleeve or stiffening member 3, Fig. 1, composed preferably of bamboo of about three quarters of an inch in diameter, this member being bored out to register with the turned bamboo and cemented thereto. The sleeve or stiffening member 3 tapers exteriorly and merges into the shaft body and a waterproof wrapping or whipping 4 is wound around the parts at this point to reinforce 80 and strengthen the joint. This sleeve may be produced from any suitable material. It may, instead of being produced from a single piece, be composed of a plurality of sections as in Fig. 7. A member or plug 5, Fig. 1, 90 of hickory or other material will be inserted in the lower end to strengthen the same. This member will be of any desired length and will be turned to fit the hole in the bamboo and will be cemented thereto. 95

Second: I start with the larger bamboo, say three-quarters of an inch, which is too stiff towards the lower part, and I render this more flexible by reducing the diameter of said lower part. This I accomplish by 100 sawing a series of V-shaped slots or openings 15, Fig. 4, in said lower part and drawing the so formed tapering tongues or members 16 together and cementing same as in Fig. 5. These V-shaped slots 15 may be of any desired length and width according to the amount of "whip" needed. The fact that they do not extend the full length

greatly facilitates and simplifies the assembling and cementing of the tapering tongues, in addition to the strength imparted by the wall at the upper end being intact or solid. 5 Three of the V-slots 15 are disclosed in Fig. 8, and the tongues or sections 16 are drawn together and cemented, as in Fig. 5. They are further secured and supported by suitable windings 17 of any suitable length 10 and in any locality. A greater number of segmental tongues or members may be produced, and in Fig. 9 six of such members are shown in end elevation.

In Fig. 3 the handle 11 having a reduced 15 end 12 is shown as positioned and secured in the upper end of a bamboo shaft 13. Rivets 14 pass through the parts and secure same in addition to the cement.

In both the "sleeve" (Fig. 1) and "tapered 20 tongue" construction (Fig. 5) I may reinforce or strengthen same by machining the internal walls by any suitable means, such as boring, reaming, broaching, drifting or filing with files formed for the purpose, and 25 inserting a reinforcing member 18 formed to register with the internal machined walls of the bamboo. I then cement the two together with a flexible waterproof cement. Bamboo of the smaller diameter, say one- 30 half inch, tends to flatness first on one side and then on the other in the sections between the nodes or joints and the inside is of corresponding shape. In order to machine the internal shape special forming 35 tools or files are required and the internal or reinforcing member or members may be shaped accordingly. This reinforcing member 18 may be of any desired length or plurality of lengths and of any desired material such as cedar, cane, hickory, etc., and 40 may be solid or bored out as indicated at the left hand end of Fig. 5, or I may use bamboo formed to fit. I may also use very thin heat treated steel tubing, "butted" or 45 slotted to enable it to twist with the torsional action of the shaft when the ball is struck. Such a construction is shown in Fig. 16 wherein the metal reinforce is designated by 30 and about which there is secured 50 and cemented a wrapping such as a leather strip 31. Cement is applied to the wrapping prior to its insertion into the bamboo and as a consequence the parts are all secured together. The knuckles or nodes are turned 55 down or otherwise reduced, as at 6, and the shaft may be whipped at such point if desired, and the longitudinally extending depressions or flat surfaces in the sides of the bamboo may be filled in any suitable manner. 60 Thus in Fig. 10 such surface, denoted by 6^a, is filled in with a mixture of sawdust or wood flour and cement, as denoted at 7, or a stripe of felt may be cemented in 65 place, as indicated by 8, at the right. The shaft may be wound with tape, as at 9, to

cover such filler and give the shaft a finished appearance. Waterproof cement or varnish is then applied.

By making the sleeve 3 of a greater or less length or by increasing or decreasing 70 the taper of the tongues 16 in Fig. 4, the point where the whip is desired to be located can be governed and secured. Suitable grip material 29 for the above shafts may be attached in the usual way as in Fig. 1. 75

To secure any of the above described shafts in the heads the methods depicted in Fig. 11 to 13 may be employed.

In Fig. 11 the bamboo is exteriorly tapered and a strip of leather 19 covered with cement is wrapped about the same. The end is then driven into the socket of the wooden head 20, the leather or other material, together with the glue, producing a strong union between the parts. 85

To secure an iron head to the shaft the construction in Fig. 13 may be employed. As in the last construction the bamboo is externally tapered and a hollow sleeve 21 of wood or other material is cemented or pinned thereon. Said sleeve is tapered externally in opposite directions from a shoulder 22, the shoulder making a close fit with the outer end of the hosel 23 of the iron. A pin 24 passing through the hosel, the sleeve, the bamboo, and through the core, or plug 5, as the case may be, firmly holds the head in place. 95

As above indicated the bamboo handle will be found applicable to implements other than golf clubs. Thus in Figs. 14 and 15 there is shown a handle suitable for a hammer comprising the bamboo member 25 having a member 26 cemented therein, the bamboo element being surrounded by a sleeve 27 cemented or pinned thereto. The opposite sides of the sleeve may be flattened to make it conform more nearly to the hole in the head. A wedge 28 may be driven into the end of the plug to secure the handle in place, Fig. 15. 100

It is conceivable that under the construction shown in Figs. 4 and 5 the V's may extend the entire length of the bamboo member, or that the upper portion thereof may split lengthwise from the upper end of the V slots where the latter stop short of the upper or outer end. 115

It is of course impossible to externally taper a piece of bamboo without removing that portion of the body which is waterproofed the strongest, but by following the methods above outlined such strength is retained. Where the bamboo length is bored through the drill may cut through the walls of the flats or depressions but such weakening is taken care of by the internal reinforcing member above described. 120

It is also found that the shaft is less liable to fracture if the shaft is secured in 130

- the head so that the flats or depressions in the bamboo appear on the top and bottom faces of the shaft.
- What is claimed is,—
1. A shaft or handle for golf clubs and the like comprising a body formed from bamboo having longitudinally tapering sections removed from the lower portion thereof so as to produce a plurality of tongues in the lower section of the shaft, combined with means for holding the tongues in close relation.
  2. A shaft or handle for golf clubs and the like comprising a body formed from bamboo having V-shaped sections removed from the lower portion thereof so as to produce a plurality of tongues tapering toward their lower ends; and a core to which said tongues are secured.
  3. A shaft or handle for golf clubs and the like comprising a body formed from bamboo, the lower end whereof is cut to produce a plurality of tongues tapering toward their lower ends; a core to which said tongues are secured; and means for weighting and stiffening the upper end of the shaft.
  4. A shaft for golf clubs and the like formed from a piece of bamboo of the required length; a filler cemented in the exterior depression natural to the bamboo; and a wrapping for the shaft thus produced.
  5. In combination with a bamboo shaft having its lower end externally tapered; a tapered sleeve mounted thereon; and a head having an internally tapered socket to receive the sleeve and the shaft end.
  6. In combination with a bamboo shaft having its lower end externally tapered; a sleeve mounted thereon, said sleeve being externally tapered in reverse directions; and a head having an internally tapered socket to receive the lower end of the sleeve.
  7. A shaft for golf clubs and the like formed from a piece of bamboo of the required length, said length being strengthened by an internally positioned metal tube, said tube being split longitudinally.
  8. A shaft for golf clubs and the like formed from a piece of bamboo of the required length, said length being strengthened by an internally positioned metal tube, said tube being split longitudinally and provided with a wrapping cemented to the tube and the inner wall of the bamboo.
  9. A shaft for golf clubs and the like formed from a piece of bamboo of the required length, said length being strengthened by an internally positioned metal tube, said tube being split longitudinally and provided with a leather wrapping cemented to the tube and the inner wall of the bamboo.
  10. In a golf club, the combination of a shaft formed from a growth of bamboo; a head secured to the lower end thereof; and means for stiffening the upper part of the shaft throughout a material portion thereof.
  11. A golf club comprising a head having a tapering shaft socket, a tubular shaft having one end located concentrically within but of less diameter than the socket and an adapter surrounding said shaft and tapering from an intermediate point toward each end, one tapering end being seated within the socket and the other tapering end extending upwardly from the socket and closely embracing the shaft whereby localization of bending stress in a single plane is prevented.
  12. A golf club comprising a tubular shaft, a head having an inwardly tapering shaft socket and a non-metallic adapter seated in said socket around the end of the shaft and gradually tapering above and away from the socket to distribute the strains due to flexure or torsion through a considerable length of the shaft.
  13. An adapter for connecting shafts to the heads of golf clubs formed with an axial bore for the reception of the end of the shaft and an external contour cylindrical in cross section and tapering from an intermediate point toward each end, one of said ends being adapted to seat in the socket of the head and the other to closely embrace and extend along the shaft above the socket whereby flexure strains will be cushioned and distributed in the shaft.
  14. An adapter for connecting shafts to the heads of golf clubs formed of non-metallic, non-resonant material with an axial bore for the reception of the end of the shaft and an external contour cylindrical in cross section and tapering from an intermediate point toward each end, one of said ends being adapted to seat in the socket of the head and the other to closely embrace and extend along the shaft above the socket whereby flexure strains will be cushioned and distributed in the shaft.
  15. A golf club comprising a tubular shaft formed of bamboo with an internal hollow metallic reinforcing element; a head having an inwardly tapering shaft socket; and a non-metallic adapter seated in said socket around the end of the shaft and gradually tapering above and away from the socket to distribute the strains due to flexure or torsion through a considerable length of the shaft.

In testimony whereof I have signed my name to this specification.

ALLAN E. LARD.
